STARTING SYSTEM FOR FREE PISTON UNITS

Kenneth C. Cooper, Portland, Conn., assignor to
United Aircraft Corporation, East Hartford,
Conn., a corporation of Delaware

Application January 28, 1944, Serial No. 520,072

10 Claims. (Cl. 222—3)

1

This invention relates to an accumulator device particularly adapted for controlling the admission of gas to a free-piston engine-and-compressor unit for starting. In certain respects the invention is a modification of that described in the copending application of Cooper, Serial No. 495,926, filed July 23, 1943, now Patent No. 2,441,186, dated May 11, 1948.

In the above application the accumulator valve is controlled by a piston connected to the valve and moving in a cylinder to one end of which gas under pressure is admitted for holding the valve closed. Venting of the cylinder permits the valve to open. A feature of this invention is the admission of a positive pressure to the cylinder for causing the valve to open rather than using a drop in pressure for this purpose.

Another feature of the invention is a valve structure in which the valve is held closed by pressure on the control piston applied directly to the piston from the accumulator chamber and the valve is caused to open by applying the same pressure to the other side of the piston.

Other objects and advantages will be apparent from the specification and claims, and from the accompanying drawings which illustrate an embodiment of the invention.

Fig. 1 is a sectional view through a free-piston unit incorporating the starting device.

Fig. 2 is a diagrammatic view of the starting system.

Fig. 3 is a sectional view on line 3—3 of Fig. 2.

The unit shown includes an engine cylinder 10 having reciprocating pistons 12 and 14 to which compressor pistons 16 and 18 in cylinders 20 and 22 are integrally connected. Sleeves 24 and 26 attached to the pistons complete the reciprocating piston assemblies. The sleeves in combination with stationary pistons 28 and 30 form air spring cylinders.

The piston assemblies are moved apart by the burning of fuel injected into engine cylinder 10 as by a device 32. Air compressed in the air spring cylinders on the power stroke returns the piston assemblies. The assemblies are always maintained at equal distances from the center of the engine cylinder by a linkage, which may include racks 34 extending from the compressor pistons.

Intake manifold 38 conducts air to intake valves 40 through which air alternately enters opposite ends of the compressor cylinders. The compressed air leaves the cylinders through discharge valves 42, also at opposite ends of the compressor cylinders and passes through scavenging manifold 44 through ports 46 and 48 which are uncovered

2

by pistons 12 and 14 at the end of the power stroke, thereby permitting air to be blown through the engine cylinder and exhaust ports 50 and 52 into exhaust manifold 54.

Starting devices 56 and 58 for the unit are mounted in air spring pistons 28 and 30. The devices are similar and device 58 will be described in detail. Piston 30 forms a housing held within the unit by a threaded ring 60 and having an accumulator chamber 62 in which gas under pressure is collected in readiness for starting. This chamber communicates with the air spring cylinder through a port 64 closed by a poppet valve 66. The stem 68 of this valve is slidable in a guide 70 on a cap 72 which closes the end of chamber 62. Valve 66 closes port 64 by movement toward the storage chamber and is opened by movement away from the chamber so that pressure of gas within the chamber opens the valve. Pressure of gas in the air spring tends to hold the valve closed during operation of the unit.

Cap 72 has a bore forming a cylinder 74 which receives a piston 76 on the end of valve stem 68. The inner end of cylinder 74 is connected with the storage chamber by one or more ports 78. A coil spring 80 in the cylinder moves the piston toward valve closing position. A head 82 closes the outer end of cylinder 74 and is held in position by studs 84 extending through both head 82 and cap 72.

30 A casing 86 on head 82 has a bore 88 in which a plunger 90 is slidable. One end of bore 88 is closed by head 82, the other end by a cover plate 92. Gas under pressure is admitted to the inner end of bore 88 through a channel 94 in casing 86. 35 With plunger 90 in the position shown, gas entering the inner end of the bore is guided into chamber 62 through a channel 96 communicating with a passage 98 in casing 86, cap 72, head 72, and the head of piston 30.

40 Passage 98 intersects bore 88 in alignment with another passage 99 which communicates with the outer end of cylinder 74. Plunger 90 is normally in a position to cut off fluid connection between passages 98 and 99, and has a groove 100 which, when the plunger is moved to the opposite end of its stroke, as limited by the pin 101, connects these passages and permits gas to flow through channel 99 into the outer end of cylinder 74, to cause valve 66 to open.

50 For moving plunger 90 to the inner end of its stroke, casing 86 has a gas inlet passage 102 which is connected by a groove 103 in plate 92 to the outer end of bore 88. When gas under pressure enters this inlet passage, it moves plunger 90 into a position to close channel 96 and to connect pas-

sages 98 and 99 to establish fluid connection between chamber 62 and the outer end of cylinder 74. When this occurs, the pressures on opposite sides of piston 76 are balanced and the pressure on valve 66 opens the valve for the escape of gas into the air spring.

In starting the unit, gas under pressure is first admitted through channel 94 until a predetermined pressure is built up in chamber 62. After this pressure is reached, gas under pressure is admitted through channel 102 thereby moving plunger 90 to close passage 96 and to cause valve 66 to open. Before this action occurs, the piston assemblies of the unit will have been moved to starting position. The sudden inrush of air into the air springs from chambers 62 in starting devices 56 and 58 will move the piston assemblies rapidly toward each other.

The starting devices 56 and 58 may be controlled by an automatically operating valve 104 which controls the admission of gas under pressure to channel 94 and passage 102. Valve 104 includes a casing 106 having a bore in which a valve plunger 108 is mounted, the plunger being normally held in the position shown by a spring 110. The tension of spring 110 may be adjusted by a nut 112 engaging threads in casing 106 to control the pressure in chamber 62 at which the starting device operates.

Casing 106 has an inlet port 114 connected to a source of gas under pressure, and an outlet port 116 connected by a conduit 118 to channel 94. Another outlet port 120 spaced from port 116 is connected by a conduit 122 to passage 102. In the normal position of plunger 108 a groove 124 in the plunger connects ports 114 and 116 and another groove 126 connects port 120 to the end of casing 106. When plunger 108 is shifted to the other end of its stroke, as limited by a threaded ring 128, groove 124 connects inlet port 114 with port 120, and another groove 130 connects port 116 to a vent port 132.

For moving plunger 108, the end of casing 106 has a nut 133 with a through passage 134. Nut 133 clamps a bushing 135, the end of which forms a valve seat engaged by the end of plunger 108. Passage 134 is connected by a branch conduit 136 to conduit 138 which connects with inlet port 114. Branch conduit 136 has an adjustable throttle valve 140 which provides a restriction greater than any restriction from conduit 138 to the chamber 62. When the desired pressure is developed in chamber 62, the pressure in passage 134 acting on the end of plunger 108 moves the plunger against the action of spring 110 to connect port 120 to inlet port 114 for procuring opening of valve 66 for starting the unit.

A small bleed passage 142 in casing 106 provides fluid connection from the end of plunger 108 to groove 130 which connects with vent port 132. This permits gas leaking past the end of plunger 108 to be vented so that the plunger will not be moved from the position shown until the desired pressure has been built up in chamber 62.

A passage 144 in casing 86 connects passage 99 with groove 103 in cap 92 and is closed by a check valve 146. After the starting unit has operated and conduit 122 is vented by plunger 108 returning to the position shown, gas at the right of piston 76 in cylinder 74 may escape past valve 146 so that piston 76 may move into a position for closing poppet valve 66.

It is understood that the invention is not limited to the specific embodiment herein illustrated and described, but may be used in other ways without

departure from its spirit as defined by the following claims.

I claim:

1. In an accumulator device, a housing having a storage chamber and an outlet port for the chamber, a valve closing the port and movable to open position by pressure in the chamber acting on said valve, a piston and cylinder one of which is connected to said valve, inlet means for admitting fluid under pressure to said chamber, a connection from said chamber to the cylinder at one side of the piston for admitting pressure to the cylinder to hold the valve closed, and means for admitting fluid under pressure to the other end of said cylinder for causing the valve to open and for simultaneously closing said inlet means.

2. In a valve structure for the rapid delivery of a measured quantity of compressed fluid to a chamber, a housing having a storage chamber therein mounted adjacent to said first chamber and having an outlet port providing communication between said chambers, a valve closing said port and movable by pressure in said storage chamber in a direction for opening the port, a piston and cylinder, one of which is connected to the valve, means for admitting fluid under pressure for said storage chamber to one end of the cylinder for holding the valve closed, and inlet means for introducing fluid under pressure to said storage chamber, in combination with means for introducing fluid under pressure to the other end of said cylinder for causing the valve to open and for simultaneously closing said inlet means.

3. In a valve structure for the rapid delivery of a measured quantity of compressed fluid to a chamber, a housing having a storage chamber therein mounted adjacent to said first chamber and having an outlet port providing communication between said chambers, a valve closing said port and movable by pressure in said storage chamber in a direction for opening the port, a piston and cylinder, one of which is connected to the valve, means for admitting fluid under pressure from said storage chamber to one end of the cylinder for holding the valve closed, and inlet means for introducing fluid under pressure to said storage chamber, in combination with means for introducing fluid from said storage chamber to the other end of said cylinder for balancing the pressures on the piston and causing the valve to open and for simultaneously closing said inlet means.

4. In a valve structure for the rapid delivery of a measured quantity of compressed fluid to a chamber, a housing having a storage chamber therein mounted adjacent to said first chamber and having an outlet port providing communication between said chambers, a valve closing said port and movable by pressure in said storage chamber in a direction for opening the port, a piston and cylinder one of which is connected to the valve, means for admitting fluid under pressure from said storage chamber to one end of the cylinder for holding the valve closed, and means for introducing fluid under pressure to said storage chamber in combination with means automatically operative when the pressure in the storage chamber reaches a predetermined value for admitting fluid under pressure to the other end of said cylinder for causing the valve to open and for simultaneously closing the fluid inlet.

5. In a valve structure for the rapid delivery of a measured quantity of compressed fluid to a chamber, a housing having a storage chamber therein mounted adjacent to said first chamber

and having a port providing communication between said chambers, a valve closing said port and movable by pressure in said storage chamber in a direction for opening the port, a piston and cylinder one of which is connected to the valve, means for admitting fluid under pressure from said storage chamber to one end of the cylinder for holding the valve closed, a fluid inlet to the chamber and means automatically operative when the pressure in said storage chamber reaches a predetermined value for admitting fluid from said storage chamber to the other side of the piston for causing the valve to open and for simultaneously closing the fluid inlet.

6. In a valve structure for the rapid delivery of a measured quantity of compressed fluid to a chamber, a housing having a storage chamber therein mounted adjacent to said first chamber and having a port providing communication between said chambers, a valve closing said port and movable by pressure in said storage chamber in a direction for opening the port, a piston and cylinder one of which is connected to the valve, means for admitting fluid under pressure from said storage chamber to one end of the cylinder for holding the valve closed, a fluid inlet to the chamber, a valve movable by fluid pressure for closing the fluid inlet and for admitting fluid from said storage chamber to the other side of the piston for causing the port closing valve to open.

7. In a valve structure for the rapid delivery of a measured quantity of compressed fluid to a chamber, a housing having a storage chamber therein mounted adjacent to said first chamber and having a port providing communication between said chambers, a valve closing said port and movable by pressure in said storage chamber in a direction for opening the port, a piston and cylinder one of which is connected to the valve, means for admitting fluid under pressure from said storage chamber to one end of the cylinder for holding the valve closed, a fluid inlet to the chamber, a plunger valve movable by fluid under pressure for closing the fluid inlet and for simultaneously admitting fluid from said storage chamber to the other side of the piston and a pressure responsive valve for admitting fluid under pressure to the end of said plunger valve for actuating it at a pre-determined point in the operation of the structure.

8. In an accumulator device, a housing having a storage chamber and an outlet port for the chamber, a valve closing the port, a cylinder and

a piston, one of which is connected to said valve, means for introducing fluid under pressure to one end of said cylinder for holding the valve closed, an inlet to said chamber, means for closing said inlet, and means associated with said inlet closing means for introducing fluid under pressure to the other end of the cylinder simultaneously with the closing of said inlet, the introduction of fluid to said other end of the cylinder operating for balancing the pressures on the piston to cause the valve to open.

9. In an accumulator device, a housing having a storage chamber and an outlet port for the chamber, a valve closing the port, a piston connected to said valve, said housing having a bore in which the piston is slideable, inlet means for admitting fluid to said chamber, means for closing said inlet means, said housing having a passage for admitting fluid from the chamber to the said bore at one side of the piston for holding the valve closed, and means associated with said inlet closing means for admitting gas under pressure to the opposite side of the piston for causing the valve to open simultaneously with the closing of said inlet means.

10. In an accumulator device, a housing having a storage chamber and an outlet port for the chamber, a valve closing the port, a piston connected to said valve, said housing having a bore in which the piston is slideable, inlet means for admitting fluid to said chamber, means for closing said inlet means, said housing having a passage for admitting fluid from the chamber to the said bore at one side of the piston for holding the valve closed, and means associated with said inlet closing means for admitting gas under pressure to the opposite side of the piston simultaneously with the closing of said inlet, the introduction of fluid to said other end of the cylinder operating to balance the pressures on the piston for causing the valve to open.
